UNITED STATES PATENT OFFICE

DUSTON KEMBLE, OF LISBON, OHIO.

JET-LIFT FOR WELLS.

1,258,418.

Specification of Letters Patent. Patented Mar. 5, 1918.

Application filed December 26, 1916. Serial No. 138,705.

To all whom it may concern:

Be it known that I, DUSTON KEMBLE, citizen of the United States, residing at Lisbon, in the county of Columbiana and State 5 of Ohio, have invented certain new and useful Improvements in Jet-Lifts for Wells, of which the following is a specification.

My invention pertains to an improvement in jet lifts for wells, the object being to 10 provide a device having a central suctional inlet area and an annular cone-shaped operating jet nozzle or ejector which is adapted to raise the fluid in a pipe well where the normal level of the fluid is too low or too 15 near the bottom for satisfactory operation of an air lift.

A further feature of the invention resides in utilizing a single centrally-located jet nozzle and suction inlet in the lower portion 20 of the lift apparatus without using the annular space between the inner pipe and the casing for the downflow of the operating current, which arrangement permits the inner pipe to be of less diameter and weight and 25 expense than if it were used for the upflow of both jet and suction output. A still further object of the invention is in providing a suction inlet into the center of the operating jet instead of placing it outside of the 30 jet; as this arrangement not only gives a compact form of the suction area, which is small at great depths, but also reduces the flow friction loss to a minimum in both jet and suction streams, and at the same time 35 affords the best lift of the liquid by atmospheric pressure into a cone-shaped space from which it is drawn upward by the jet at an accelerating velocity until the two are made one stream in the throat of the ejector 40 nozzle. Another object is embodied in means whereby the casing foot is protected, and the ball-valve is drawn out with the inner pipe when the latter is lifted from the well, and also whereby the liquid in one 45 or both long pipes may be drained off without being lifted when the inner pipe is lifted.

In the accompanying drawings, Figure 1 is a sectional view longitudinally of my improved apparatus, the upper and lower portions of the pipes being broken away. Fig. 50 2 is a similar view to Fig. 1, but at right angles thereto.

Figs. 3 and 4 are transverse sections of the 55 apparatus on lines 3—3, Fig. 1, and 4—4, Fig. 2, respectively.

The apparatus consists of a large pipe 2 having a pipe 3 of smaller diameter sleeved therein with an ample sized annular space 4 between the respective walls of said pipes, 60 and the outer pipe 2 is provided with a removable cap 5 at its lower end through which an intake tube 6 is adapted to project to a well-point (not shown). The bottom surface of cap 5 is of irregular curvature 65 and relatively heavy and the inner pipe 3 is provided with an enlarged foot 7 in screw engagement therewith and with the intake tube 6. Foot 7 rests upon cap 5 and a circular packing of rubber, or other suitable material occupies a groove in the bottom of the head to prevent leakage, and the outer surface of foot 7 is channeled longitudinally to provide fluid passages open to the outer space 4 and the space beneath the bottom 75 of the foot, and a flaring valve seat 8 is formed centrally in said bottom opposite the end of the intake tube 6. Foot 7 is also provided with two down-flow channels 9 internally of less length than the head and the 80 respective ends of these channels are curved inwardly and register with openings 10 and 11 at different elevations in the pipe 3. However, a throat member 12 is removably 85 screwed within pipe 3 which closes the main passage in pipe 3 between the upper and lower sets of openings, the said member terminating above the lower openings 11 and having outwardly-curved by-passes 13 at its upper end adapted to register with the 90 upper openings 10, in this way producing a divided flow for the fluid which passes downwardly through pipe 3 and which issues into the converging throat 14 centrally at the bottom of member 12. Throat 95 14 is contracted to its greatest extent at a point about mid-length of said member where it begins to flare outwardly and merges finally with two oppositely-disposed curved ducts 15 arranged in the same vertical plane but at right angles to the oppositely disposed down-flow channels 9 in foot 7. Openings 16 in inner pipe 3 register with the outlet ends of ducts 15 to permit the fluid to escape into the annular 105 space 4 above head 7. The direction of flow of the operating fluid under pressure is downwardly through inner pipe 3, thence through by-passages 13 into the down-flow channels 9, and thence upwardly through 110 the throat 14 and ducts 15 into space 4, and suitable provision is made at the top of

both pipes to deliver the fluid into inner pipe 3 and to discharge the fluid from outer pipe 2.

This flow of fluid is utilized to lift and carry away a portion of fluid or liquid which is adapted to be taken into the bottom of foot 7 through valve seat 8, and this end is best effected by using a converging suction nozzle 17 which is adapted to project more or less into the converging throat 14. Adjustment of the suction nozzle is easily effected as said element is made as a separate piece and is screw-engaged with inner pipe, and when the parts are assembled the suction opening is centrally related to throat 14 and an annular space 18 of greater or lesser area provided within the throat around the mouth of said suction nozzle. This annular space may also be referred to as the jet area.

The bottom portion of the suction nozzle is open and flares outwardly to the screw-threaded outer surface thereof, and a series of radial ribs 19 extend inwardly from the flaring surface to check the ball valve 20 from excessive upward movement and prevent closure of the passage under an induced flow of the liquid passing through the valve seat.

In operation, the operating pressure in the jet is far greater than the possible vacuum pressure in the suction channel, special provision being made in the form or shape of the latter to allow room for a sufficient quantity of liquid to enter the suction area under low or atmospheric pressure to supply a contracted portion of the channel with sufficient liquid at a higher velocity for a given ratio of output to the quantity of liquid flowing in the jet. This principle must be observed in calculating the design or layout for any given output with a given height of lift, since otherwise the liquid will not enter the suction area by atmospheric pressure fast enough to keep up with the normal work of the operating jet, and the result will be a partial vacuum that must interfere seriously with the operating efficiency. However, where the design is properly laid out, the current issuing from the suction inlet is surrounded by a rather wide annular jet area 18 just inside of the common channel, and the outer portion of liquid in this lower part of the cone-shaped space over the suction inlet is caught up and thrown by the jet through the contracted outlet or throat 14 with high velocity, while new liquid comes in at lower velocity through the suction inlet. The preferred plan is to arrange the twin down-flow channels for the jet outside of the inner pipe, but these may be arranged straight down on the inside of the inner pipe instead of being carried outside, as shown in the drawings. A reverse relation of the suction in-

let and operating jet may also be adopted, that is, the operating jet may be centrally disposed within an annular suction inlet communicating with pipe 6, but the arrangement shown is preferred.

70

What I claim is:

1. In a jet lift for wells, a double-chambered well casing having cross-communicating passages between the chambers provided with a contracted throat and an annular jet space centrally opposite said throat and having a valved intake at its bottom and a suction inlet centrally of said annular jet space.

2. In a jet lift for wells, inner and outer pipes and a throat member and suction inlet member for the inner pipe and channels leading upward from said inlet member in the inner pipe, and an intake member at the bottom of said pipes.

85

3. In a jet lift for wells, a set of pipes in spaced sleeved relation having a cap at the bottom end thereof and provided with an intake, a cross-channeled member within the inner pipe with one pair of channels in open communication with the space between the pipes, and an inlet member centrally located between said intake and channeled member.

90

4. In a jet lift for wells, a set of pipes in spaced sleeved relations having a communicating channel and a pair of crossed channels above and below the central channel set substantially at right angles with each other therebetween, and an inlet member adjustably mounted relatively to said communicating channel.

100

5. In a jet lift for wells, a set of pipes in spaced sleeved relation having crossed-communicating channels with a contracted throat centrally of said pipes, and a suction inlet member of nozzle form adjustably mounted within said inner pipe centrally opposite said throat.

105

6. In a jet lift for wells, a plurality of pipes in spaced sleeved relation having a cap and an intake extension at corresponding ends thereof, a foot and a throat member for the inner pipe having crossed channels therein in open communication at their respective ends with the separate spaces within said pipes, a nozzle member interposed between said throat member and intake extension, and a valve within said foot beneath said nozzle member.

110

7. In a jet lift for wells, a pair of pipes of different diameters united in spaced sleeved relation, a cap for the outer pipe and an intake member extending therefrom, a head for the inner pipe adapted to bear against said cap, a throat member within the inner pipe having crossed communicating channels opening at their respective ends into the said inner and outer pipes, and a suction inlet member in the form of a nozzle.

115

125

130

- zle arranged centrally opposite the said throat member.
8. In a jet lift for wells, inner and outer pipes, a cap for the outer pipe, an intake connection for the inner pipe extending through said cap, a suction nozzle opposite said intake, and a throat member and foot for the inner pipe having channels therein in open communication at their opposite ends with the interior of said inner and outer pipes, respectively, and having a contracted throat of bell-shape surrounding said suction nozzle.
9. In a jet lift for wells, a pair of pipes of different diameter in spaced sleeved relation, a cap and intake extension for said pipes, a foot affixed to the inner pipe in ²⁰ slideable engagement with the outer pipe, a throat member secured within said inner pipe, said foot and throat member having channels with diverging passages at their respective ends in open communication with the respective interiors of said pipes and converging in a flaring throat centrally of ²⁵ said throat member, a suction nozzle centrally within said flaring throat, and a check valve for said intake extension.
- Signed at Lisbon, in the county of Columbiana and State of Ohio, this eighth day of December, 1916.

DUSTON KEMBLE.
